UNITED STATES PATENT OFFICE.

WILLIAM J. DURING, OF SYRACUSE, NEW YORK, ASSIGNOR TO PRECISION CASTINGS COMPANY INCORPORATED, OF FAYETTEVILLE, NEW YORK, A CORPORATION OF NEW YORK.

DIE-CASTING MACHINE.

Application filed April 23, 1925. Serial No. 25,301.

This invention relates to a certain new and improved die-casting machine.

The main objects of the invention are the production of a die-casting machine of 5 strong and durable construction that is rapid and automatic in its operation of producing castings, and in which the closing of the dies and their maintenance in closed position is mechanically effected, and therefore positive, and certain, and in which the sequence 10 of the various steps in the operation of producing a casting is accurately timed, due to the particular correlation of the several actuating means.

15 A further advantage of this invention resides in the particular structure whereby the dies are moved to and from the nozzles and to and from each other at particular related times and positions of movement.

20 A further advantage resides in the production of a structure whereby a saving and economy of fluid under pressure utilized for forcing the molten metal from the pot into the dies is effected.

25 Other objects and advantages relate to the details of the structure, all as will more fully appear from the following description, taken in connection with the accompanying drawings, in which:

30 Figure 1 is a top plan view of the machine.

Figure 2 is a longitudinal sectional view on line 2—2, Figure 1.

Figure 3 is a lateral sectional view on 35 line 3—3, Figure 1.

Figure 4 is a vertical sectional view through the plug for closing the inlet opening to the pot, taken on line 4—4, Fig. 1.

Figure 5 is a sectional view on line 5—5, 40 Figure 1.

Figure 6 is a section on line 6—6, Figure 2.

Figure 7 is a section on line 7—7, Figure 1.

Figure 8 is a vertical section through the main shaft the drum including the valve- 45 actuating cams, the valve chest and valves of the mechanism for controlling the fluid under pressure which forces the molten metal from the pot into the dies.

Figure 9 is a section on line 9—9, Fig- 50 ure 8.

Figure 10 is a section on line 10—10, Figure 8.

Figure 11 is a section on line 11—11, Figure 8.

The machine as here illustrated comprises 55 a main frame —1— of substantially rectangular form and supported at its four corners by legs and feet 2, 3, 4 and 5, the legs being connected by longitudinal side rails —6— and end rails —7—, and the side 60 rails are connected together at intermediate points by cross rails —8— and —9— to form a rigid structure.

The furnace may comprise a separate casting —100— of substantially rectangular 65 form and supported at its four corners by legs and feet —11—, —12—, —13— and —14—, two legs adjacent the main frame —1— being rigidly secured to the main frame by bolts —15— so that the furnace 70 structure is rigid with the main frame structure.

The main shaft —10— extends longitudinally of the frame —1— and is journaled in the end-walls —7— and the intermediate 75 cross-walls —8— and —9—, and it may, as shown, be provided with end-thrust bearings to facilitate its rotary movement when end thrust pressure is applied to it.

The main shaft may be driven in any suitable manner, as for instance by worm-gear 80 —16— keyed to the shaft and meshing with worm —17— on shaft —18— which carries at one end a portion of a clutch-element 85 —19—, the other portion of which element is carried by shaft —20— journaled in the frame —1—, and carrying the gear —21— keyed to it meshing with the small gear —22— mounted on the stub shaft —23—, small gear —22— being integral with the 90 larger gear —23'— which meshes with the comparatively small gear —24— on the armature shaft —25— of motor —26—.

It will be obvious that the reduction gear- 95 ing described is illustrative of one means for driving the shaft —10— at a desired speed, preferably considerably lower than the speed of the armature shaft, and that the clutch —19— is interposed so that an operator may at will disconnect the main 100

shaft —10— from the driving means, as for instance through the medium of a lever —27— connected by rock-arm —28— and link —29— to a yoke —30— slideable on cross-bar —31— and engaged with one element of the clutch for moving the same into driving or non-driving position in a usual and well-known manner.

The main shaft —10— carries near its central portion a drum-cam —32—. This drum-cam, as perhaps best illustrated in Figures 2 and 7, is of cylindrical form, and has a groove or channel —33— formed in its surface. The portions —34— of the groove near the opposite ends of the drum extend substantially circumferentially of the drum, and are of a desired length preferably substantially as illustrated, and these end-portions are connected by diagonal longitudinally extending portions —35— upon opposite sides of the cylinder, and connecting the end portions —34— to form a continuous groove or channel, within which the drive-pin ring —36— is positioned, the ring being of a diameter substantially equal to the width of the groove or channel —33—, the latter being of substantially uniform width throughout its length.

The drive-pin ring, as shown, is mounted upon the reduced cylindrical lower end-portion of a drive pin —37—, which pin extends through a vertical opening in plate-member —38— constituting a portion of a sliding carriage —39—, and the plate member is formed with a circumferential recess in its upper portion for the reception of an enlarged head on the drive-pin. The other member of the sliding carriage consists of a second plate-like member 105 having vertically-extending side rails 102 and 103 and connected at their forward ends by the tail-stock 104. The plate member 105 has a central elongated slot 106 of a width and length sufficient to permit withdrawal of drive-pin —37— in any position of adjustment of the two plate-members —38— and 105— of the sliding carriage, which adjustment is permitted by the bolts 130 and 131 extending through openings in the plate 38 that substantially fit the bolts and through respective slots 107 and 108 in the plate 105.

By means of this construction, it is only necessary to drop the drive-pin into the opening in the sliding carriage —38— and its lower reduced end will project through the ring —36— in the groove —33— and the drive-pin ring is easily removed to separate the carriage 39 from driving relation with the drum —32—.

60 The sliding carriage —39— has its opposite edges slideable in under-cut channels or grooves formed by the inwardly and upwardly inclined flanges —40— and —41— formed on a slide member —42— and for this purpose the opposite edges of the plate

member 105 which lie outside of the plate —38—, are inclined downwardly and outwardly so as to fit beneath the over-hanging portions of the flanges —40— and —41—.

In order to maintain a frictionally tight engagement of the sliding carriage —39— and the slide member —42—, a wedge member —43— is interposed at one side between the over-hanging flange —41— and the downwardly inclined portion of the adjacent edge of the carriage —38— as best illustrated perhaps in Figures 3 and 7, and set screws —44— may be provided for maintaining the frictional engagement sufficiently tight to effect the operation hereinafter described.

The slide —42— moves lengthwise of and upon the upper surface of the frame —1— between the opposed vertical flanges —45— and —46— and with its opposite edges beneath the respective confining bars —48— and —49— secured to the flanges —45— and —46— respectively by means of bolts —50— and —51— respectively. The slide —42— has a longitudinal slot or opening of a width adapted to receive and permit relative sliding movement of the conical depending portion —52— on the plate-member —38— through which the driving pin —37— extends. In order to maintain the slide —42— in the desired tight relation with respect to flanges —45— and —46—, a wedge member —53— may be interposed between the flange —45— and the adjacent edge of the slide —42— and set screws —54— may be provided extending through the flange —46— for contact with the wedge —53— for maintaining it in desired relation with respect to the slide —42—.

The tail-stock 104 has secured to it a die-carrier —55— to which one of the dies —56— may be secured in any well known manner. The other die section —57— may be secured to the bolster plate —58— in any suitable manner, and has an inlet port —59— aligned with the gate member —60— carried by the bolster-plate —58—.

This bolster-plate may, as shown, be secured to the forward end of the slide —42— in any suitable manner, as by bolts —61—. The casting 100 constitutes an enclosure for a suitable furnace —62— which carries the pot —63— adapted to contain molten metal. This pot rests upon and is secured to a plate —64— bolted to the casting 100 in any suitable manner, as by bolts —65—. The pot includes a suitable nozzle —66— for contact with the gate member —60— during the operation of the machine, as hereinafter described.

The pot is further provided with an inlet for metal normally closed by means of a closure-plug —67— which is held to its seat or released for removal by means of cam —68— formed on a rotary roll or shaft —69—.

equipped with an operating handle —70—. Pipe —71— is provided for conveying fluid under pressure, such as air, to the pot for ejecting the molten metal therefrom into the die at predetermined intervals when the die is in proper relation, and a baffle —72— is provided for rendering the application of pressure more uniform.

The means for automatically controlling the supply of fluid under pressure to pipe —71— and the pot —63— and for permitting the discharge of fluid under pressure therefrom at predetermined intervals, and for effecting a material saving of the fluid under pressure consists as here illustrated in a cylinder —73— mounted upon the main shaft —10— and carrying three cams —74—, —75— and —76— adapted respectively for actuating valves —77—, —78— and —79— arranged in the valve-box —80—. This valve box —80— is formed with three valve chambers —81—, —82— and —83— for receiving the respective valves —77—, —78— and —79— and with a passageway —84— in communication with each of the valve chambers —81—, —82— and —83— under control of their respective valves. Further, the passage —84— is in direct communication with the pipe —71— leading to the pot —63—. The chamber —81— is in communication with the pipe —85— leading to the reservoir —86— for fluid under pressure and in which fluid is adapted to be forced under desired pressure by pump 87. The chamber —82— is at all times in communication with the pipe —71— and the valve 78 controls communication between the chamber 82 and the pipe 88 which penetrates the valve-box 80 above the valve 78 and leads to a relatively low-pressure reservoir or tank 89 for communication with a low pressure pump —90— through pipe 91 and high pressure pump 87 through pipe 92. The valve chamber 83 is at all times in communication with the pipe 71 and the valve 79 controls communication between the chamber 83 and pipe 93 which penetrates the valve-box 80 and is at all times in communication with the atmosphere.

For the purpose of effecting the desired operation, the cam 74 has a valve-operating projection —94— of comparatively short circumferential length, and the cam 75 has a similar projection of perhaps slightly greater circumferential length, while the cam 76 has a circumferential projection extending throughout a considerable portion of its circumference.

This construction results in the fact that valve 77 is maintained open for a comparatively short length of time. Valve 78 is maintained open for a slightly greater length of time, while valve 79 is maintained open a comparatively long time, thereby effecting the operation hereinafter described.

The apparatus here shown comprises a means for automatically ejecting a casting from the die —56— in the form of a rack 110 extending through the tail-stock 104 and through a portion of the die-carrier —55— 70 for securing to a plate-member 111 having a second-plate member 112 secured to it in any suitable manner, and carrying a series of ejecting pins 113 which extend through the other portion of the die-carrier 75 —55— and through the die —56—. Loose pins are also provided which extend through the die —56— through the forward portion of the die-carrier —55—, and normally abut against the plate 112. The rack 110 is 80 mounted in a pedestal 115, and is actuated by a gear 116 mounted on or formed integrally with a shaft 117 journaled in the opposite walls 102 and 103 of the sliding carriage as illustrated.

A second pedestal —118— is bolted at the rear of the machine to a cross-plate 119 secured to the frame and carries in a split bearing an adjustable stop-bar 120 longitudinally aligned with the rack —110— so as 90 to limit the rearward movement of the rack, at a desired point, and this for the purpose of automatically ejecting a casting from the die-section —56— by moving plates 111 and 112 carrying the pins 113 forwardly to force 95 a casting from the die when the dies are separated a predetermined amount. The rack may, however, be hand-operated when desired by means of crank 140. The movable pins 114, when the dies are brought together, contact with the die-section 57 and return the pins 113 to their original position if that has not been automatically effected during previous movement of the machine parts. The bolster-plate —58— may be 100 cooled, as by water flowing through an annular jacket —122— on the face of the plate, the jacket being provided with flow and return pipes 123 and 124.

The operation of the machine will be 110 understood from the following:

With the motor in operation and the clutch engaged, and parts of the machine in the position illustrated in Figure 2, as the cam 32 rotates with the drive-ring —36— in 115 the cam groove, the carriage 39 will be moved forwardly carrying with it sliding member 42 upon which the bolster-plate —58— is mounted, this simultaneous movement resulting from the frictional engagement of these parts, and this simultaneous movement of the carriage 39 and the plate 42 will continue until the nozzle 66 is tightly engaged with the gate-member —60— 120 whereby the further movement of plate 125 —42— is prevented.

Carriage 39 will continue to move independently of the plate —42— until the drive-ring 36 reaches the straight circumferential portion 34 of the cam 32, at which time the 130

die-sections will be in tight relation, and adapted to receive molten metal for producing castings. Proper adjustment for effecting this tight relation at the position of the drive-ring as specified is provided for by bolts 130 and 131 in the respective slots 107 and 108. At this point cam 74 opens valve 77 and permits air under pressure to pass through pipe 71 from tank 86 to the pot 63 whereby molten metal is forced by the desired pressure, as for instance 400 pounds, into the dies. Cam 74, being of short circumferential length, maintains valve 77 open for a brief period of time, after which it is automatically closed by the spring illustrated. At this time cam 75 opens valve 78 and permits the air under pressure to flow from the pot through pipe 71 to the pipe 88, and from thence to the low pressure tank 89, in which under these circumstances, a pressure may be produced of approximately 300 pounds.

Valve 78 is closed after a brief period by the spring illustrated, and then valve 79 is opened by cam 76 to bring the pot 63 through pipe 71 into communication with the pipe 93 and the atmosphere to relieve the pressure in the pot, and this condition of atmospheric pressure is maintained during the greater portion of each rotation of the shaft —10— and until at the proper position of the dies, cam 74 again opens valve 77. In the meantime when the cam 75 has permitted the closure of valve 78, and after the valve 79 is opened to produce atmospheric pressure in the pot 63, the cam 32 begins to move slide 42 and carriage 39 rearwardly to first separate the gate-member 60 from the nozzle 66. The frictional engagement of slide member 42 and carriage 39 which is maintained by wedge 43 causes a simultaneous rearward movement of these parts to the position of the slide member shown in Figure 2 when the rear end of said member 42 strikes the forward portion of the cross-plate 119, thereby limiting the movement of the slide-member 42, at which point independent movement of the carriage 39 begins, whereby the dies 56 and 57 are separated, and the casting may remain in the die 56 until such time as the rear end of the rack 110 strikes the stop-bar 120, at which time the rack is maintained stationary, while the carriage continues to move, whereby the plates 111 and 112 are moved forwardly carrying pins 113 to thereby eject the casting. Pins 114 are provided for the purpose of returning plates 111 and 112, and ejecting pins 113 from the rack 110 to the position shown in Figure 2, should that not be automatically effected during forward movement of the carriage 39. This is effected by contact with the forward ends of pins 114 with the die 57 when the dies are being brought to closed position.

This operation repeats itself automatically from time to time in accordance with the speed of the motor, and the interposed reduction gearing.

A considerable saving in air under pressure, and therefore, operating power, is effected by reason of the fact that the air under pressure is exhausted from the pot into the tank 89 where a pressure of perhaps 300 pounds is maintained so that pump 87 is only required to raise the pressure of the air supplied to it from tanks 89 about 100 pounds to obtain desired operating pressure.

Altho I have shown and described a specific construction of machine as illustrative of a perhaps preferred embodiment of my invention, I do not desire to restrict myself to the details of the structure or the form and relation of the parts thereof, except as the same may be specifically set forth in the claims hereto appended.

I claim:

1. A die-casting machine comprising a frame, a shaft journaled on the frame, a 90 slideable member mounted on the frame and adapted to carry a die-section, a sliding carriage adapted to carry the other die-section, and frictionally engaged with the sliding member, and cooperative means on the main 95 shaft and the sliding carriage for effecting simultaneous reciprocating movement of the carriage and sliding member within limits of movement of the latter, and then positive movement of the carriage independent of the 100 slide member.

2. A die-casting machine comprising a frame, a shaft journaled on the frame, a slideable member mounted on the frame and adapted to carry a die-section, a sliding carriage adapted to carry the other die-section and frictionally engaged with the sliding member, a drive pin engaged with the sliding carriage, a member mounted on the shaft and having a cam-groove adapted to receive 110 a portion of the drive-pin for effecting simultaneous reciprocating sliding movement of the carriage and slide member within the limits of movement of the latter, and then movement of the carriage independent of 115 the slide member.

3. A die-casting machine comprising a frame, a shaft journaled in the frame, a pot having a nozzle, a sliding member mounted on the frame and adapted to carry a die-section for moving the latter into and out of position to receive metal from the nozzle, a sliding carriage mounted on the slide member and frictionally engaged with the slide member and adapted to carry the other die-section, and cooperative means on the shaft and the sliding carriage for effecting simultaneous sliding movement of the slide-member and the sliding carriage to move the first-named die-section into and out of posi- 130

- tion to receive metal from the nozzle, and for effecting an independent positive movement of the sliding carriage to relatively move the dies into and out of closed position.
5. A die-casting machine comprising a frame, a shaft journaled in the frame, a pot having a nozzle, a sliding member mounted on the frame and adapted to carry a die-section for moving the latter into and out of position to receive metal from the nozzle, a sliding carriage mounted on the slide-member and frictionally engaged with the slide-member and adapted to carry the other die-section, a cylinder mounted on the shaft, and having a cam-groove and a drive pin engaged with the sliding carriage and having a portion positioned in said groove for effecting a reciprocating movement of the sliding carriage, together with and independently of the slide-member.
5. A die-casting machine comprising a main frame, a slide member mounted on the main frame and having an elongated slot therein, a shaft journaled in the main frame below the slide member, a cam mounted on the shaft for rotation therewith, a sliding carriage mounted on the slide member in frictional contact therewith for moving the slide member within the limit of movement of the latter, and a drive-pin engaged with the sliding carriage, and having a portion adapted to contact with said cam for effecting reciprocating movement of the sliding carriage.
35. A die-casting machine comprising a main frame, a slide member mounted on the main frame and having an elongated slot therein, a shaft journaled in the main frame below the slide member, a cam mounted on the shaft for rotation therewith, a sliding carriage mounted on the slide-member and frictionally engaged therewith for simultaneous sliding movement, a drive pin engaged with the sliding carriage and extending through said slot and having a portion adapted to engage said cam for effecting simultaneous sliding movement of the slide member and sliding carriage within the limits of movement of the former, and then its independent movement of the sliding carriage.
7. A die-casting machine comprising a main frame, a slide member mounted on the main frame for horizontal reciprocating movement and formed with an elongated slot, said slide member adapted to carry a die-section, a shaft mounted on the main frame below the slide member, a cylinder mounted on the shaft for rotation therewith and formed with a cam groove, a sliding carriage mounted on the slide member and frictionally engaged therewith for simultaneous movement, said sliding carriage adapted to carry the other die-section, a drive pin engaged with the sliding carriage and extending through the slot in the slide
- member, and having a portion seated in the cam-groove in the said cylinder for effecting a simultaneous sliding movement of the slide-member and sliding carriage within the limit of movement of the former, and then 70 independent movement of the sliding carriage.
8. A die-casting machine comprising a main frame, a slide member mounted on the main frame adapted to carry a die section, a sliding carriage mounted on the slide member and adapted to carry the other die-section, co-operative means on the shaft and sliding carriage for effecting movement of the sliding carriage, a pot for containing 80 molten metal, a compressed air tank, means of communication between the compressed air tank and the pot, a valve in such communication, and means rotating with the main shaft for opening said valve at predetermined intervals to bring the compressed air tank into communication with the pot and a second air tank in communication with the pot for exhausting air from the same for later return to the pot under increased pressure.
9. A die-casting machine comprising a main frame, a slide member mounted on the main frame adapted to carry a die section, a sliding carriage mounted on the slide member and adapted to carry the other die-section, co-operative means on the shaft and sliding carriage for effecting movement of the sliding carriage, a pot for containing 90 molten metal, a compressed air tank, means of communication between the compressed air tank and the pot, a valve in such communication, means rotating with the main shaft for opening said valve at pre-determined intervals to bring the compressed air tank into communication with the pot, a valve in such communication, and means rotating with the main shaft for opening said valve at pre-determined intervals to bring the compressed air tank into communication with the pot, a valve in such communication, means of communication between the pot and the low pressure air-tank, a valve in such communication, and means rotating with the main shaft for opening said valve to bring the pot into communication with the low pressure air-tank immediately after communication is cut off between the high pressure air tank and the pot.
10. A die-casting machine comprising a main frame, a slide member mounted on the main frame adapted to carry a die-section, a sliding carriage mounted on the slide member and adapted to carry the other die-section, cooperative means on the shaft and sliding carriage for effecting movement of the sliding carriage, a pot for containing 100 molten metal, a compressed air tank, means of communication between the compressed air tank and the pot, a valve in such communication, means rotating with the main shaft for opening said valve at pre-determined intervals to bring the compressed air tank into communication with the pot, a valve in such communication, and means rotating with the main shaft for opening said valve to bring the pot into communication with the low pressure air-tank immediately after communication is cut off between the high pressure air tank and the pot.
- 115
10. A die-casting machine comprising a main frame, a slide member mounted on the main frame adapted to carry a die-section, a sliding carriage mounted on the slide member and adapted to carry the other die-section, cooperative means on the shaft and sliding carriage for effecting movement of the sliding carriage, a pot for containing 110 molten metal, a compressed air tank, means of communication between the compressed air tank and the pot, a valve in such communication, means rotating with the main shaft for opening said valve at pre-determined intervals to bring the compressed air tank into communication with the pot, a valve in such communication, and means rotating with the main shaft for opening said valve to bring the pot into communication with the low pressure air-tank immediately after communication is cut off between the high pressure air tank and the pot.
- 120
10. A die-casting machine comprising a main frame, a slide member mounted on the main frame adapted to carry a die-section, a sliding carriage mounted on the slide member and adapted to carry the other die-section, cooperative means on the shaft and sliding carriage for effecting movement of the sliding carriage, a pot for containing 125 molten metal, a compressed air tank, means of communication between the compressed air tank and the pot, a valve in such communication, means rotating with the main shaft for opening said valve at pre-determined intervals to bring the compressed air tank into communication with the pot, a compara- 130

- tively low pressure air tank, means of communication between the pot and the low pressure air tank, a valve in such communication, means rotating with the shaft for opening said valve to bring the pot into communication with the low pressure air tank immediately after communication is cut off between the high pressure air tank and the pot, means of communication between the pot and the atmosphere, a valve controlling such communication and means rotating with the shaft for opening said valve to bring the pot into communication with the atmosphere after communication has been cut off between the pot and the low pressure air tank.
11. A die-casting machine comprising a main frame, a slide member mounted thereon and carrying a die-section, a pot having a nozzle, a sliding carriage mounted on the slide member and frictionally engaged therewith for simultaneous movement within limits, a shaft journaled in the frame below the slide member, a cam member mounted on the shaft, a drive pin engaged with the sliding carriage and with the cam member for effecting movement of the slide member and the sliding carriage to bring the die-sections into position to receive metal from the nozzle, a compressed air-tank, means of communication between the tank and the pot, a valve controlling such communication, and means driven by the said shaft for opening said valve to bring the compressed air tank into communication with the pot at the time the die-sections are in position to receive metal from the nozzle, a second air-tank, means of communication between the pot and the second air-tank, a valve in such communication, and means driven by the shaft for opening said valve to bring the pot into communication with the second air-tank after communication between the first-named tank and pot has been cut off, means of communication between the pot and the atmosphere, a valve in such communication, and means driven by the shaft for opening said valve to bring the pot into communication with the atmosphere after communication between the pot and the second-named tank has been cut off.
12. A die-casting machine comprising a main frame, a slide member mounted thereon and carrying a die-section, a pot having a nozzle, a sliding carriage mounted on the slide member and frictionally engaged therewith for simultaneous movement within limits, a shaft journaled in the frame below the slide member, a cam member mounted on the shaft, a drive-pin engaged with the sliding carriage and with the cam member for effecting movement of the slide member and the sliding carriage to bring the die-sections into position to receive metal from the nozzle, a compressed air-tank, means of communication between the tank and the pot, a valve controlling such communication, means driven by the said shaft for opening said valve to bring the compressed air tank into communication with the pot at the time the die-sections are in position to receive metal from the pot, a second air tank, means of communication between the pot and the second air tank, a valve in such communication, and means driven by the shaft for opening said valve to bring the pot into communication with the second air tank after communication between the first-named tank and the pot has been cut off.
13. A die-casting machine comprising a main frame, a slide member mounted thereon and carrying a die-section, a pot having a nozzle, a sliding carriage mounted on the slide member and frictionally engaged therewith for simultaneous movement within limits, a shaft journaled in the frame below the slide member, a cam member mounted on the shaft, a drive-pin engaged with the sliding carriage and with the cam member for effecting movement of the slide member and the sliding carriage to bring the die-sections into position to receive metal from the nozzle, a compressed air-tank, means of communication between the tank and the pot, a valve controlling such communication, means driven by the shaft for opening said valve to bring the compressed air tank into communication with the pot at the time the die-sections are in position to receive metal from the pot, a second air-tank, means of communication between the pot and the second air-tank, a valve in such communication, and means driven by the shaft for opening said valve to bring the pot into communication with the second air-tank after communication between the first-named tank and pot has been cut off, means of communication between the pot and the atmosphere, a valve in such communication, and means driven by the shaft for opening said valve to bring the pot into communication with the atmosphere after communication between the pot and the second-named tank has been cut off.
14. A die-casting machine comprising a frame, a shaft journaled on the frame, a slide member mounted on the frame and adapted to carry a die-section, a sliding carriage adapted to carry the other die-section and frictionally engaged with the slide member, a drive pin engaged with the sliding carriage, a member mounted on the shaft and having a cam-groove adapted to receive a portion of the drive-pin for effecting simultaneous reciprocating sliding movement of the carriage and slide member within the limits of movement of the latter, and then movement of the carriage independent of the slide member, and means carried by the frame for ejecting a casting from a die-section when the sliding carriage reaches a predetermined position during its sliding movement.
15. In a die casting machine, a frame, a pot having a nozzle, a slide member and a sliding carriage capable of simultaneous movement and of movement independently of each other, a die-section carried by the slide member, a second die-section carried by the sliding carriage mechanism for automatically moving said slide member and said sliding carriage to carry the die-sections into and out of cooperative relation with each other and with the said nozzle.
16. In a die casting machine, a frame, a

- pot having a nozzle, a slide member and a sliding carriage capable of simultaneous movement and of movement independently of each other in a plane substantially parallel to the axis of the nozzle, a die-section carried by the slide member, a second die-section carried by the sliding carriage mechanism for automatically moving said slide member and said sliding carriage to carry the die-sections into and out of cooperative relation with each other and with the said nozzle.
17. In a die casting machine, a frame, a pot having a nozzle, a slide member mounted on the frame for movement toward and from the nozzle, a sliding carriage mounted on the slide member and capable of movement simultaneously with and independently of the slide member, a die section carried by the slide member, a second die section carried by the sliding carriage and mechanism for automatically moving said slide member and said sliding carriage simultaneously to bring the die section on the slide member into operative relation for receiving metal from said nozzle, said mechanism acting thereafter to further slide the sliding carriage with respect to the slide member to bring the die-sections into cooperative closed relation.
18. In a die-casting machine, a nozzle for supplying metal, a sliding carriage, a die section carried thereby, a slide member, a cooperating die-section carried thereby, said sliding carriage and said slide member having a frictional engagement of sufficient tightness so that normally within limits, the movement of one will simultaneously move the other, means for moving the sliding carriage to initially separate the dies from the nozzle, means for limiting the movement of the slide member simultaneously with the carriage, said moving means acting thereafter to cause continued movement of the sliding carriage to separate the dies.

In witness whereof I have hereunto set my hand this 8th day of April, 1925.

WILLIAM J. DURING.
